UNITED STATES PATENT OFFICE.

CHARLES H. LA DUE, OF NEW YORK, N. Y., ASSIGNOR TO THE LA DUE MECHANICAL MOVEMENT COMPANY, OF NEW YORK.

MECHANICAL MOVEMENT.

SPECIFICATION forming part of Letters Patent No. 307,964, dated November 11, 1884.

Application filed June 5, 1884. (No model.)

To all whom it may concern:

Be it known that I, CHARLES H. LA DUE, a citizen of the United States, and a resident of New York city, in the county of New York and State of New York, have invented a certain new and useful Mechanical Movement, of which the following is a specification.

My invention has for its object mechanism for converting a reciprocating rectilinear motion into rotary motion, and vice versa, applicable as an attachment to piston-rods of steam-engines and of locomotives to produce rotary motion in the belt-wheel, fly-wheels, or drivers of said structures, or to produce a reciprocating motion in punches, pump-rods, or the like apparatus, when used in combination with a crank or similar device caused to revolve; and I effect the results stated by attaching to a rectilinearly-reciprocating piston-rod or connecting-bar a head having a slot or groove formed therein, in which slot or groove the equivalent of a crank-pin works, and to which is given a rotary motion by the action of the slot or groove.

25 In the accompanying drawings like letters indicate like parts in all the figures.

Figure 1 illustrates my invention applied to the driving-wheels of a locomotive, and is a vertical section taken on the median line of the 30 piston-rod. Fig. 2 illustrates a top plan view of the invention as shown in Fig. 1. Fig. 3 illustrates a vertical longitudinal section of the "head."

A A are the ordinary driving-wheels of a locomotive, mounted on their respective shafts or axles, B B, as usual, the axles being attached to the frame of the locomotive in any known manner.

40 C C are pins, which may be substantially the same as the ordinary crank-pins attached to locomotives as now generally constructed, and which are rigidly attached to the spokes or plate of the wheel at such point between the tread and center of the wheel as desired, depending upon the desired length of piston-stroke.

D is an ordinary cylinder attached to the frame of the locomotive in any known manner.

50 E is the piston, and F the piston-rod. The

cylinder is fitted with a stuffing-box, G, and other appliances, all as usual.

H H are what I will call the "driving-heads." There is one for each driving-wheel; and they preferably consist of a block or plate of metal, 55 although they may be made of other material, made integral with the piston-rod, or as a separate piece rigidly attached to it in any suitable manner. It may, however, be constructed of several pieces bolted or otherwise fastened together, all that is essential being that there should be a slot, groove, or equivalent feature for the reception of the pin C. Through it is formed a slot, I, of such width that it will receive the crank-pin C, and of a length equal 65 to a little more than the diameter of the circle described by the crank-pin, and its center lengthwise should preferably be coincident with the center of rotation. Instead of the slot completely through the head H a groove may 70 be employed.

K is a connecting-rod rigidly attaching the two driving-heads H H together, thus being practically an extension of the piston-rod F. The connecting-rod is preferably squared in 75 cross-section, or at least made of some shape other than round, and it passes through a hole of the same shape as itself made in the guide or way block L, which is rigidly attached to any suitable part of the frame of the locomotive. This guide or way block serves not only to support the connecting-rod, but, owing to the hole through it being of some shape other than round, and the connecting-rod fitting it, it prevents the connecting-rod from turning 80 over, and consequently the driving-heads are held in a position to keep them in proper engagement with the crank-pins.

I' is another similar guide or way block behind the second driver, its purpose being the 90 same as that of L. Any suitable means for supporting, guiding, and preventing rotation of the connecting-rods and the driving-heads may be substituted for these guide or way blocks.

95 It will of course be understood that when my invention is used on locomotives or engines in which there are two cylinders and piston-rods the crank-pins of the respective driving-wheels, belt-wheels, or fly-wheels, as the case 100

may be, are set on the quarter relative to each other, as usual in such structures, so that dead-centers are avoided.

I provide for lost motion and wear of the 5 sides of the slots I and of the crank-pins C as follows: Illustrated in Fig. 3, M M are two solid bars or plates, of brass or other suitable metal, which form the friction-surfaces between the crank-pins and the inside of the slot, and 10 in order that the wear may come on them, and not on the sides of the slot in the driving-head; they are made a trifle shorter than the slot is long, and project inwardly beyond the edges of the slot; and they are rigidly attached to 15 the follower-keys N N, which are set in recesses made for them in the driving-heads, the back edges of the recesses and of the keys having an inclination from a true vertical line, but the front edges of the keys, which rest against 20 and support the friction-bars M, are preferably perfectly vertical, and the wearing-surfaces of the bars made also perfectly vertical, or at least on lines at right angles to the plane of movement of the piston or other rod. The friction-bars or the keys, one or both, are made of such 25 width that they bind strongly against the sides of the recess in which they are contained, so that they cannot be moved, except by a blow of a hammer on the upper end of the keys, or 30 by the action of the nuts O on the ends of the keys; and whenever the friction-bars or the crank-pins wear away, so that lost motion results, the keys are forced downwardly by such 35 blow of a hammer on their upper ends, which causes them to slide slightly down through the recess provided for them, and thus by the action of the inclined surfaces of the back side of the keys and of the recesses in which they are contained the friction-bars are forced slightly 40 inward toward the center of the slot I and the lost motion is taken up. I also provide the threaded nuts O, which engage with the ends of the keys, which are suitably threaded for the purpose, so that the keys may be drawn 45 down and the adjustment of the friction-bars attained, if desired, with greater exactness than by the employment of the strokes of a hammer. The friction-bars may, however, if desired, be the full length of the slot I, and be attached to 50 the keys by a dovetailed groove, so that the keys will slide on them.

The operation of my invention is simple. Assume that the pin C is in the position shown in Fig. 1. Steam is let on in front of or behind 55 the piston, as the case may be, and, depending thereon, the piston-rod will move in or out of the cylinder, and will move the driving-head in accordance with its movement. The bars at the sides of the slot or groove I will impinge against the pin C and rotate the wheel or shaft, as the case may be, to which the pin is attached. Thus at each double stroke of the piston the pin C describes a complete revolution.

65 When my invention is employed to operate punches, pump-rods, and such structures, of

course the relative arrangement of the parts is altered, as will be understood by any one familiar with this art. For instance, a crank or equivalent device will be the source of 70 power, from which a projecting pin or equivalent device will engage with the slot I, and the rod corresponding to the piston-rod will be supported and compelled to move rectilinearly by a suitable box or ways, through or over 75 which the rod will move.

When my invention is applied to ordinary stationary engines, a pin similar to a crank-pin may be attached to an arm or equivalent device fastened to the main shaft of the engine, or upon any suitable part of the main balance or belt wheel, or in any other desired manner, and in any suitable place.

There are many advantages flowing from my invention. Among them are the following: 85 The engine or locomotive is made lighter; the cumbrous yoke usually used on engines is done away with, and also the pitman and its cross-head; the joints between the pitman and the cross-head in which it works, which are 90 continually getting out of order, are done away with; there are fewer bearings requiring oil; also, there is a reciprocating motion, pure and simple, not a combined reciprocating and circular movement; hence the apparatus moves 95 with more smoothness and occasions much less tremor than when both these motions are present; also, my invention enables an engine to start nearer the dead-point than by the old constructions; also, the valve-rods may be 100 connected to the piston or connecting rod more conveniently than on the present engines, and there being fewer parts and a less number of moving surfaces, accident to the engineers are not so apt to occur.

105 I do not limit myself to the details of construction; they may be considerably departed from and still my invention be employed.

It is obvious that my device may be set vertically as well as horizontally, and also at any 110 desired angle.

Having described my invention, I claim—

1. A rectilinearly-reciprocating rod provided with a slot or groove, a crank-pin adapted to slide in the slot or groove, and a guide 115 for the rod, substantially as and for the purposes set forth.

2. The combination of a piston-rod, a guide for the free end of the piston-rod, a connecting-rod, one end of which engages with the 120 free end of the piston-rod, and a groove or slot formed in or attached to the connecting-rod, and a crank-pin adapted to slide in the said slot or groove, substantially as and for the purposes set forth.

3. The combination of the driving-head H, provided with the slot or groove I, and a crank-pin adapted to slide in the slot or groove I, substantially as and for the purposes set forth.

125 4. The combination of the driving-head H, provided with the slot or groove I, and the

wearing-bars M and the keys N, substantially as and for the purposes set forth.

5. The combination of a slotted or grooved block or plate guided and supported and a crank-pin adapted to slide in the groove or slot in the block, whereby a rotary motion imparted to the crank-pin will produce a reciprocating motion in the block, and a reciprocating motion imparted to the block will pro-

duce a rotary motion in the crank-pin, substantially as and for the purposes set forth.

Signed at New York, in the county of New York and State of New York, this 4th day of May, A. D. 1884.
